UNITED STATES PATENT OFFICE.

HOWARD R. HUGHES, OF HOUSTON, TEXAS.

LUBRICATOR FOR ROLLER DRILLS.

Application filed November 21, 1921. Serial No. 516,704.

To all whom it may concern:

Be it known that I, HOWARD R. HUGHES, a citizen of the United States, residing at Houston, Harris County, Texas, have invented a certain new and useful Improvement in Lubricators for Roller Drills, of which the following is a full, clear, and exact description, such as will enable others skilled in the art to which it appertains to make and use the same.

My invention relates to an improvement in lubricators to be employed with roller earth boring drills in drilling wells for oil, gas, sulphur, water, etc., and in mining. The invention has particular application to drills employed in deep well operations on which rolling cutters are employed. These cutters are adapted to withstand heavy strain and must be properly lubricated in order to serve their function.

The object of my invention is to provide a lubricator which will be positive in its operation and adapted during the operation of a drill, to force the lubricant to the bearings against the pressure of the head of flushing fluid within the hole.

A further object is to provide a lubricator of this kind which will be operated through the rotation of the drill itself and wherein the rolling of the cutters upon the material at the bottom of the well will serve to actuate means to force the lubricant to the bearings.

Another object is to provide a means for forcing lubricant to the bearings of an earth boring drill which will be independent of the pressure or of the flow of the flushing fluid within the well.

Further objects will appear to one skilled in the art after reading the more detailed description which follows.

Referring to the drawings herein, Fig. 1 illustrates an ordinary type of earth boring drill, partly in central longitudinal section and partly in elevation and showing my lubricator attached thereto, said lubricator being in central longitudinal section. Fig. 2 is a transverse section on the line 2-2 of Fig. 1, and Fig. 3 is an elevation 50 of the retaining ring removed.

My invention is shown as being applied to the usual type of rock drill now employed in the rotary system of deep well drilling. It comprises a head 1 divided longitudinally into two parts and having a threaded upper shank 2 for connection

to a drill stem, not shown, by means of which the said drill may be rotated. The drill is provided with two frusto conical shaped cutters 3 adapted to roll upon the formation being drilled and to disintegrate the same by means of the chisel action of cutting teeth 4. These cutters are mounted upon bushings 5 and are held in place thereon by means of locking rings 6, threaded on the inner face of the said cutters. The bushings 5 are threaded upon a downwardly inclined stub shaft or support 7. This type of cutter is shown in my prior Patent No. 1,143,271 and need not be further described. The cutter and bushing are adapted to bear against the nonfriction washer 8 separating the cutter from the body of the drill head.

There is centrally of the upper end of the shank 2 a small threaded nipple 9 to which is adapted for attachment by means of a coupling 10, a lubricator barrel 11. This barrel 11 comprises a tube formed to stand upwardly within the drill stem and provide a chamber large enough to accommodate the desired amount of lubricant. It is closed at the upper end by means of a cap 12, said cap having a central opening or perforation 13 to allow the passage therethrough of flushing fluid.

Fitting closely within the interior of the lubricator barrel is a piston 14, having upper and lower cups 15 thereon of compressible material adapted to maintain a close fit with the interior of the barrel. This plunger or piston is prevented from rotating by the fitting of a projection thereon within a lateral groove 16 extending longitudinally of the chamber. The said plunger is threaded interiorly for connection with a threaded shaft or rod 17. This rod extends the full length of the barrel 11 and is threaded throughout the major portion of its length. Said rod is connected at its lower end to a flexible joint or coupling 18.

The operation of the threaded shaft 17 is accomplished by connecting through a shaft 19 mounted in an inclined position within the head 1 of the drill and connected at its lower end to a beveled gear 20. This gear is adapted to rotate partly within a small groove or chamber 21 in the head of the drill and meshes on its outer side with teeth formed at 22 on the outer face of the locking ring 6 of the cutter. These teeth are but two in number so as to im-

part an intermittent rotation to said shaft thus operating the lubricator at a slow speed. The shaft 19 is connected at its upper end by means of a universal joint 5 shown at 18 to the shaft 17 as previously described, so that it may act to rotate the said shaft.

In the operation of the drill it will be noted that the rolling of the cutters 3 upon 10 the bottom of the hole will cause the teeth 22 on the ring 6 to actuate the gear 20 and rotate the shaft 19. This motion will be communicated through the joint 18 to the threaded shaft 17 and will thus force the 15 piston 14 downwardly within the lubricator barrel. It is contemplated of course, that the usual rotation of the drill in its ordinary clockwise direction, as viewed from above, will drive the shaft 17 in the proper 20 direction to force the lubricator piston downwardly.

Lubricant within the barrel 17 below the piston will thus be forced downwardly and will find passage through the ducts 23 in 25 the head of the drill to the bearings of the cutters in the usual manner. The pressure of the flushing fluid within the lubricator will be exerted with somewhat greater force upon the upper surface of the piston 14 than 30 at the lower end of the oil ducts leading to the bearings. This pressure cannot affect the piston which is moved only by the rotation of the threaded shaft 17. Its tendency would be to assist, however. The operating parts may therefore be made of light 35 construction as they will have only a light load to operate. This lubricator has the advantage that it will operate whenever the cutters are operating and need lubrication. 40 It will be entirely independent of the flow of flushing fluid and any clogging in the action of the flushing apparatus will in no wise affect the flow of the lubricant. It will be positive in its action and will have advantages obvious to one skilled in the art 45 without further description.

What I claim as new and desire to protect by Letters Patent is:

1. In a roller earth boring drill, a drill 50 head, a roller cutter thereon, a toothed retaining ring on the inner face of said cutter, a lubricator barrel on said head, a piston in said barrel, ducts connecting said barrel and the bearings of said cutter, and 55 means to force said piston longitudinally of said barrel comprising a central threaded rod in said barrel to which said piston is operatively engaged, a flexible joint at the lower end of said rod, a rotatable shaft in 60 said head connected to said joint, a gear thereon, and a cooperating gear formed by said retaining ring, whereby the rotation

of said cutter will rotate said rod and move said piston.

2. In a roller earth boring drill, a drill 65 head, a roller cutter thereon, a lubricator barrel on said head, a piston in said barrel, ducts connecting said barrel and the bearings of said cutter, and means to move said piston longitudinally of said barrel comprising 70 a central rod to which said piston is threadedly engaged, a rotatable shaft in said head, the upper end of which is flexibly connected to said rod and the opposite end of which is provided with a bevel gear, 75 and means on the inner face of said cutter engaging with said gear whereby the rotation of said gear will rotate said shaft and actuate said lubricator piston.

3. In a roller earth boring drill, a drill 30 head, a roller cutter thereon, a threaded nipple centrally of the upper end of said head, a lubricator barrel secured thereto, oil ducts in said head connecting said barrel and the bearings of said cutter, a piston 85 in said barrel, a threaded rod centrally of said barrel to which said piston is operatively engaged, and means to rotate said rod and drive said piston comprising a shaft in said head flexibly connected to said 90 rod, a gear on said shaft, and a gear on said cutter meshing therewith.

4. In a roller earth boring drill, a head, roller cutters thereon, a lubricator barrel on said head adapted to deliver lubricant to 95 the bearings of said cutters, a threaded rod longitudinally of said barrel, a piston on said rod, means to prevent rotation of said piston, and means to rotate said rod comprising a shaft flexibly connected to said 100 rod and geared at its lower end to the inner face of one of said roller cutters.

5. In a roller earth boring drill, a head, a roller cutter thereon, a removable retaining ring on the inner face of said cutter, a 11 lubricator barrel on said head, a piston in said barrel, a rod having screw connection with said piston, a shaft connected to said rod and a gear on said shaft connected with gear teeth on said retaining ring, whereby 1 said shaft and rod may be rotated by the rolling of said cutter.

6. In a roller earth boring drill, a head, a roller cutter thereon, a lubricator barrel 1 on said head, ducts from said barrel to the 1 bearings of said cutter, a piston in said barrel, a threaded rod operatively engaged with said piston and means on said cutter connected with said rod to impart a slow intermittent rotation thereto.

In testimony whereof, I hereunto affix my signature this the 16th day of November, A. D., 1921.

HOWARD R. HUGHES.
